UNITED STATES PATENT OFFICE.

EDSON POTTER, OF TOLEDO, OHIO.

MAIL-BAG CATCHER.

SPECIFICATION forming part of Letters Patent No. 763,925, dated June 28, 1904.

Application filed October 21, 1903. Serial No. 177,873. (No model.)

To all whom it may concern:

Be it known that I, EDSON POTTER, a citizen of the United States, residing at Toledo, in the county of Lucas and State of Ohio, have invented new and useful Improvements in Mail-Bag Catchers, of which the following is a specification.

My invention has relation to improvements in mail-bag catchers and cranes; and the objects are, first, to provide improved means of the kind named for detachably holding the mail-bag in position to be engaged and released from its support by any appliances used for that purpose on a passing car; second, to associate in such an apparatus or mechanism a mail box or receptacle standing normally open and into which a mail-bag may be thrown and the receptacle closed automatically by the impact or force of the mail-bag therein.

20 The invention will be hereinafter specified fully, its parts and elements described and combination stated, and the asserted novelty particularly pointed out and distinctly claimed.

25 I have fully and clearly illustrated the improvements in the annexed drawings, to be taken as a part of this specification, and in which—

Figure 1 is a side elevation of the complete device, showing the mail-bag receptacle from the rear. Fig. 2 is a view in end elevation, showing a mail-bag suspended from the crane, the mail-bag receptacle in side elevation, and the reverse position assumed by the mail-bag 35 and mail-receptacle indicated in dotted lines. Fig. 3 is a vertical central section through the base, the pedestal, the inner rotatable sleeve, and the vertically-movable hollow supporting-stem and the mail-receptacle support with 40 the crane-post broken off. Fig. 4 is a top plan view of the device or apparatus. Fig. 5 is a plan view of the device, partly in horizontal section, taken on the line 5 5 of Fig. 1. Fig. 6 is a vertical central section through the 45 inner rotatable sleeve, showing the cam or screw lifting-groove. Fig. 7 is a side elevation of the lower portion of the vertical movable standard, showing one of the vertical slots in which the shaft of the lifting-pinion works 50 and showing the pin which engages in the cam-

groove of the rotatable sleeve. Fig. 8 is a detail view of the upper portion of the pedestal, showing the recesses in which the lug on the lever which rotates the inner sleeve locks. Fig. 9 is a detail plan view, partly in horizontal section, taken on the line 9 9 of Fig. 8. Fig. 10 is a detail view of the lever which rotates the inner sleeve and also serves to lock the parts against rotation.

In the drawings like parts appearing in different illustrations are designated by similar reference-notations.

Referring to the drawings, A designates any suitable support, on which is placed and secured the base-plate 1 of the machine, having 65 formed thereon or secured therein a hollow cylindrical pedestal 2, extending vertically to such a height and made of such diameter as may suit it to the purposes intended. In the base of the pedestal 2 is rotatably arranged a 70 hollow cylindrical sleeve 3, formed with an annular collar 4, which rests on the upper end of the hollow pedestal 2. To the collar 4 is pivotally hung a lever 5, formed with a lug or projecting part 6, which engages in locking-recesses 7 8, made in the pedestal at its upper end. This lever 5 swings up to horizontal position when it is used to reverse the position of the mail-receptacle and the crane and then may be swung down to vertical position 80 and engage in one of the locking-recesses, thus holding the mechanism in the position to which it may have been turned. In the inner face of the rotatable sleeve 3 is formed a cam-groove 9, in which engages a pin 10, fixed at 85 the proper point in the stem of the support or post which carries the mechanism.

11 designates a hollow post loosely disposed in the sleeve 3 and formed or provided in its interior with a vertical rack 12, with which 90 engages a pinion 13, mounted on a shaft 14, which extends through oppositely-arranged vertical slots 15, made in the walls of the post 11 and journaled on the upper end of the sleeve 3, as indicated in the drawings. The 95 ends of the shaft 14 are squared, so that a crank-handle may be connected thereto to rotate it and cause the pinion to elevate the post or to cause it to descend after having been moved up. It will be perceived that 100

when the post 11 is elevated by the pinion it is carried straight up for a distance by the engagement of the pin 10 in the vertical part of the groove 9, and then when the pin 10 reaches the turn in the cam groove or slot it follows therein and turns or swings the post, with the elements attached thereto, substantially into reverse position, and when the pin reaches the end of the slot, which is made with a slight descent or incline below the highest point in the slot, the post is held in the elevated position. The upper end of the post 11 is formed with a T-head 16, one end of which is turned up to vertical direction and has connected thereto a post 17, which is made the requisite length. To the upper end of the post 17 is pivotally connected the crane 18, the connection being made by means of forked arms 19, which extend to the rear of the pivotal support, as seen in the drawings, the arms serving as levers to raise and lower the crane. To the free end of each of the arms 19 are connected rods 20, which extend down along the side of the post and have their lower ends connected to the arms of a forked lever 21, mounted at the bend of the T-head 16 in such a way that the arms of the lever will swing inward past the pivotal point, as seen in Fig. 1 of the drawings, and hold the crane in horizontal position, as shown. At the outer end the crane is made with outwardly-directed arms 22 23, provided with slits 24, which divide the arms into jaws formed with recesses at or near the free ends, between which the straps, as 25, of the mail-bags are inserted and detachably held, substantially as seen in Fig. 2 of the drawings, wherein mail-bags, as 26, are shown suspended from the arms of the crane. In the T-head 16 is secured a sleeve 27, which at its outer end is recessed half-way round, as at 28, to afford shoulders or stops against which the turning lever lodges when the mail-bag receiver is reversed on its axial support. In the sleeve 27 is journaled a shaft 29, held against endwise displacement by any suitable means and carrying on its outer end a cross arm or head 30. In the shaft is fixed a lever 31, by which the shaft is turned on its axis and the mail-receiver reversed. This lever holds the shaft in a fixed position by engagement with the shoulders on the end of the sleeve 27 and in this way holds the mail-bag receiver in either position to which it may be turned. 32 designates the mail-bag receiver, made, preferably, cylindrical in conformation and consisting of two semicylindrical sections 33 34, hinged together at their back edges, as at 35, and at their front meeting edges formed with broad coincident flat flanges 36, which when the receiver is closed lie in contact, as seen in the drawings, and when the receiver stands open the flanges serve as guides to direct the mail-bag into the interior of the receiver.

To the flanges are secured handholds 37 for opening the receiver. In each end piece of the receiver is formed an opening 38, one-half of said opening being in each section of the receiver, as indicated in the drawings. When the receiver is in closed position with the mail-bag inside, the straps of the bag will project through the openings.

Clipped to the ends of the cross head or bar 30 are curved flat springs 39 40, standing away from the receiver and having their ends pivotally connected to the sections thereof in such relation as to hold the sections open with the hinge tending to press forward and so that when the sections are pressed back on the hinge-line the springs will exert inward pressure and throw the sections together. Adjacent to each end of the cross-head 30 is a laterally-projecting pin 41, on which is a coil-spring 42, having one arm anchored in the cross-head and the other, as 43, extending from the section and formed at its free end with a curve or notch in which one of the straps of the mail-bag engages to hold the bag in proper position, as indicated in Fig. 2 of the drawings.

In use the apparatus is set up and secured in proper position alongside a single-track road, or in case of a double-track road it is positioned between the tracks, so as to be accessible from either. The mail-bag is then secured to the crane by the insertion of the upper looped strap in the jaws of the crane and the lower strap hooked on the proper spring-arm projecting from the mail-bag receiver. The post is then elevated, by means of the pinion and rack, to the proper height, the mail-bag receiver having first been opened if mail is to be deposited therein. In the upward movement the receiver and the crane will be turned toward the track with the mail-bag receiver open and the suspended mail-bag in the position to be released from the crane and spring-arm, and at the same time the bag to be delivered is thrown into the receiver, which closes from the contact through the action of the springs connected to the sections. When it is desired to simply reverse the direction of the mail-bag receiver, it is readily accomplished by means of the lever 31, which turns the shaft 29 and reverses the receiver, as indicated in Fig. 2 of the drawings. The crane may be swung down by swinging the lever 21 outward. The manipulation of any of the elements independently is apparent to those acquainted with such mechanisms and may be readily ascertained by persons in charge.

Having thus fully described the invention, what is claimed as new is—

1. A mail-bag receiver composed of two semicylindrical sections hinged together, and springs to hold the sections open and to close them.
2. A mail-bag receiver composed of two

sections hinged together and having broad flanges extending from their free meeting edges, and springs to hold the sections open and to close them.

5 3. A mail-bag receiver composed of two sections hinged together and having broad flanges extending from their meeting edges and coincident recesses in the meeting edges of its top and bottom, and springs to hold the 10 sections open and to close them.

4. The combination of a pivotally-mounted support formed with a cross-head, means to turn the support on its axis, springs secured to the ends of the cross-head, and a mail-bag 15 receiver composed of two sections hinged together and having the ends of the springs secured thereto.

5. The combination of a pivotally-mounted support formed with a cross-head, springs secured to the cross-head, and a mail-bag receiver composed of two sections hinged together and connected to the springs.

6. The combination of a pivotally-mounted support reversible on its axis, a cross-head on the support, and a mail-bag receiver consisting of movably-connected inclosing sections secured to the cross-head whereby the receiver is reversed with the reversible support.

7. The combination of a pivotally-mounted support reversible on its axis, a cross-head on the support, a mail-bag receiver consisting of movably-connected inclosing sections secured to the cross-head, means to reverse the support, and means to raise and lower it.

35 8. The combination of a pivotally-mounted support reversible on its axis, a cross-head on the support, a mail-bag receiver secured to the cross-head, means to reverse the support, means to raise and lower it, and means to 40 swing it on a horizontal plane.

9. A device of the character described comprising a hollow supporting-pedestal, a cylindrical sleeve rotatably placed therein and formed with a cam slot or groove, means to

rotate and lock the sleeve, a hollow post in 45 the sleeve formed with a pin to engage the cam-slot, and a hollow T-head, means to raise and lower the post, a sleeve horizontally secured in the T-head, a shaft in the sleeve reversible on its axis, a cross-head on the shaft, 50 flat springs secured to ends of the cross-head, and a mail-bag receiver composed of two sections hinged together and each section secured to the ends of the springs to hold them open and automatically close them, as described. 55

10. In an apparatus of the character described, a hollow supporting-post formed with opposite alining vertical slots, a rack-gear on the inner face of the post, a shaft placed through the slots, and a pinion on the shaft 60 to engage the rack and raise and lower the post.

11. The combination with the mail-bag receiver, of a spring-arm secured thereto adapted to engage a loop on a mail-bag, and the 65 crane formed at its outer end to detachably engage a loop on a mail-bag, substantially as described.

12. In a device of the character described, the combination with the T-head 16, of the 70 post 17, a crane pivotally secured to the top of the post, connecting-rods, and a lever connected to the rods to operate the crane, substantially as described.

13. In a device of the character described, 75 the combination with the T-head 16, of a vertical crane-support secured in the T-head, a crane pivotally mounted on the crane-support and formed at its outer end with arms formed with spring-jaws adapted to detachably take 80 in a loop on a mail-bag.

In testimony whereof I affix my signature in presence of two witnesses.

EDSON POTTER.
